UNITED STATES PATENT OFFICE.

GEORGE G. BARKER, OF SPRINGFIELD, OHIO, ASSIGNOR TO THE BAUER BROTHERS COMPANY, OF SPRINGFIELD, OHIO, A CORPORATION OF OHIO.

GRINDING-PLATE.

1,169,228.

Specification of Letters Patent. Patented Jan. 25, 1916.

Application filed May 6, 1915. Serial No. 26,362.

To all whom it may concern:

Be it known that I, GEORGE G. BARKER, a citizen of the United States, residing at Springfield, in the county of Clark and State 5 of Ohio, have invented certain new and useful Improvements in Grinding-Plates, of which the following is a specification.

My invention relates to improvements in grinding plates for grinding machinery.

10 The object of the invention is to provide improved and effective means for retarding the material in its passage from the inlet to the point of discharge so as to insure a thorough grinding of the same.

15 In the accompanying drawings:—Figure 1 is a side view of the grinding face of a plate embodying my improvements. Fig. 2 is a section on the line 2—2 of Fig. 1.

Like parts are represented by similar 20 characters of reference in the several views.

In the said drawings, 1 represents a plate having a central opening 2 to receive the material to be ground. As shown in Fig. 2, the base of the plate is tapered from the 25 opening 2 to a point near the outer periphery thereof so that it and the opposing plate will form a gradually decreasing space 3 from the centers of the plates to that point. From that point to the extreme outer per-

30 riphery the base is tapered at a more pronounced angle, as indicated at 1^a so that the extreme outer periphery of the opposing plates will be brought together so as to leave but a comparatively small space be-

35 tween the same. This construction acts to assist in holding back the material and prevents its discharge until it has been reduced to the proper fineness and at the same time allows sufficient space between the plates to

40 obtain the most desirable grinding action. The base of the plate is provided with a series of curvilinear ribs 4, these ribs being of different lengths. These ribs are preferably formed upon arcs of circles the centers

45 of which are equi-distant from the center of the plate, so that the ribs will be preferably of uniform curvature, and the arc centers are also preferably of uniform distances apart so that the ribs will thereby preferably

50 be spaced uniformly apart. It will be seen that the ribs thus formed are located in

the tapered space 3 and that it will be necessary for the ground material, as it is thrown by centrifugal force toward the outer periphery of the plate, to pass between 55 adjacent ribs, which form passageways or channels. In order to retard the passage of the material to an extent which will insure the proper grinding thereof, there is provided in the passages thus formed a series 60 of auxiliary ribs 5. These auxiliary ribs are so disposed relatively to the main ribs that they will form an obtuse angle with any radius line drawn through the center of the plate, thus preventing the formation of 65 pockets on the inner sides of these auxiliary ribs into which the material might collect.

In operation, the ground material will be drawn by centrifugal force into the tapered channels between the main ribs 4. The 70 curved form of these tapered channels assisted by the retarding ribs 5 has a tendency to hold back the material, until by the time it is discharged at the outer periphery of the plates it will be in a thoroughly ground 75 condition.

Having thus described my invention, I claim:—

1. In a grinding plate, a series of curved ribs on said plate, and a series of auxiliary 80 ribs extending from one side only of each of said curved ribs, each of said auxiliary ribs extending in such direction relatively to the curved ribs as to form an obtuse angle with an intersecting radius line on said 85 plate.

2. In a grinding plate, a series of curved ribs on said plate, all of said ribs being formed upon the arcs of circles the centers of which are substantially equi-distant from 90 one point on said plate, and a series of auxiliary ribs on one side only of each of said curved ribs, each of said auxiliary ribs extending in such direction relatively to its curved rib as to form an obtuse angle with 95 an intersecting radius line of said plate.

In testimony whereof, I have hereunto set my hand this 23rd day of April, 1915.

GEORGE G. BARKER.
